(57) **CLAIM**

The ornamental design for an unmanned aerial vehicle, as shown and described.

DESCRIPTION

FIG. 1 is a right-forward upper elevational view of an unmanned aerial vehicle, showing my new design.

FIG. 2 is a right-forward lower elevational view thereof;

FIG. 3 is a top view thereof;

FIG. 4 is a bottom view thereof;

FIG. 5 is a front view thereof;

FIG. 6 is a back view thereof;

FIG. 7 is a left-side view thereof; and,

FIG. 8 is a right-side view thereof.

The broken lines in the figures illustrate portions of the unmanned aerial vehicle that form no portion of the claimed design.

1 Claim, 8 Drawing Sheets
